DESCRIPTION

The patent or application file contains at least one drawing executed in color. Copies of this patent or patent application publication with color drawing(s) will be provided by the Office upon request and payment of the necessary fee.

FIG. 1 is a front view of a first image of a display screen with animated graphical user interface;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is an enlarged view of the ICON of FIG. 1, shown separately for completeness of illustration;

FIG. 12 is an enlarged view of the ICON of FIG. 2, shown separately for completeness of illustration;

FIG. 13 is an enlarged view of the ICON of FIG. 3, shown separately for completeness of illustration;

FIG. 14 is an enlarged view of the ICON of FIG. 4, shown separately for completeness of illustration;

FIG. 15 is an enlarged view of the ICON of FIG. 5, shown separately for completeness of illustration;

FIG. 16 is an enlarged view of the ICON of FIG. 6, shown separately for completeness of illustration;

FIG. 17 is an enlarged view of the ICON of FIG. 7, shown separately for completeness of illustration;

FIG. 18 is an enlarged view of the ICON of FIG. 8, shown separately for completeness of illustration;

FIG. 19 is an enlarged view of the ICON of FIG. 9, shown separately for completeness of illustration; and,

FIG. 20 is an enlarged view of the ICON of FIG. 10, shown separately for completeness of illustration.

The appearance of the display screen with animated graphical user interface transitions sequentially between the images shown in FIGS. 1 thru 10. The appearance of the display screen with animated graphical user interface tran-

sitions sequentially between the images shown in FIGS. **11** thru **20**. The process or period in which an image transitions to another forms no part of the claimed design.

The broken line box illustrates portions of the display screen and contains only the portion of the display screen with animated graphical user interface that is being claimed.
